UNITED STATES PATENT OFFICE.

NATHAN C. CHAPMAN, OF DETROIT, MICHIGAN, ASSIGNOR TO GAS OIL STOVE COMPANY,
OF DETROIT, MICHIGAN, A CORPORATION OF MICHIGAN.

IGNITER FOR LIQUID-FUEL BURNERS.

1,227,245.

Specification of Letters Patent.

Patented May 22, 1917.

Application filed June 17, 1916. Serial No. 104,157.

To all whom it may concern:

Be it known that I, NATHAN C. CHAPMAN, a citizen of the United States, and residing at Detroit, in the county of Wayne 5 and State of Michigan, have invented a new and Improved Igniter for Liquid-Fuel Burners, of which the following is a specification.

This invention relates to means for igniting the liquid fuel in burners of the double chimney type wherein the fuel is admitted to a trough that extends across between the lower ends of these chimneys, and its object 10 is to provide a simple, cheap and convenient device whereby the usual igniting wick can be raised up from between the chimneys and replaced when desired.

This invention consists in combination with the usual igniting wick of an oil 15 burner, of a novel metal reinforcing support therefor, and a handle or bail attached to said support whereby the support and wick can be raised and lowered as desired.

In the accompanying drawing, Figure 1 20 is a section of a stove top showing a burner partly in elevation and partly in central section. Fig. 2 is a perspective view of this improved igniter, a portion being broken away for the sake of clearness.

Similar reference characters refer to like 25 parts throughout the several views.

The structure shown in Fig. 1, is an oil 30 stove consisting of the top 1, front 2, back 3, bottom 4, legs 5, grate 6, inner chimney 7, outer chimney 8, deflector 9 and supporting bars 10. A trough 12 is shown integral 35 with the inner chimney and supporting the outer chimney. A continuation of this trough constitutes a ledge 13 over which is a cover 14. The fuel oil, usually kerosene, 40 is conveyed to the trough by means of pipes 15 and 16, the flow being controlled by means of the hand-wheel 17.

The common practice in lighting the 45 burner is to lift up the chimney from the base of the burner which holds the wick, then admit sufficient oil to moisten the asbestos wick 19, and then to apply a lighted match to the wick. Or a piece of asbestos 50 on the end of a proper holder is saturated with fuel and lighted, and then lowered down into contact with the wick. The present invention provides a simple and cheap 55 device in the form of a ring 21 to which the tongues 22 are connected, which tongues

are properly bent to hold the wick securely in position. The ring and tongues also serve to reinforce the wick. A handle or bail 23 is connected to the reinforcing means, and the wick, after being saturated, can be 60 lifted out, lighted, and then lowered down into place.

The heat from the flame at the wick soon 65 heats the trough and ledge to such a degree that the fuel oil is gasified immediately and burns with a clear blue flame at the upper end of the cylindrical space between the two chimneys.

By securing the wick between the bent 70 portions of the fingers 22, spaces are left which permit the fuel oil to flow to the wick and saturate it. The radial flange 21 holds the wick substantially concentric with the two chimneys and is of such strength that it easily retains its shape. As the wick 19 75 extends a distance above the ring 21, the flame is not interfered with by the reinforcing device.

I claim:

1. In an igniter for oil burners, the combination of a wick-reinforcing member comprising a ring and fingers connected thereto and extending downward therefrom and then inward and upward, a cylindrical wick held between the bent portions of said fingers and extending up above said ring, and a bail extending upward from said igniter. 80

2. In an igniter for oil burners, the combination of a wick-reinforcing member comprising a ring and fingers connected thereto and extending downward therefrom and then inward and upward, a cylindrical wick held between the bent portions of said fingers and extending up above said ring, and a bail extending upward from said igniter, 90 said bail consisting of a wire rod bent to form a top and parallel sides whose lower ends are attached to said reinforcing member. 95

3. In a reinforcing and transporting device 100 for the wicks of oil stoves, the combination of a cylindrical ring and fingers connected thereto and extending down and then up to securely grip a cylindrical wick, and a bail secured to two of said fingers and extending 105 upward therefrom, said ring being positioned approximately midway the ends of the wick.

4. In an igniter for oil burners having inner and outer perforated chimneys, the com- 110

bination of an annular wick, a metal ring to hold the wick, and a bail connected to the metal ring and consisting of a wire having its middle portion extending across the inner chimney and having its ends extending down between the chimneys and connected to the metal ring.

5. An igniter for oil burners having concentric chimneys, an annular wick normally at the bottom of the space between the

chimneys, a metal reinforcement for the wick, and a lifter connected to the reinforcement and extending up between the chimneys and so far above them that the lifter may be manually grasped to lift the 15 wick out above the chimneys.

In testimony whereof I sign this specification.

NATHAN C. CHAPMAN.
